FLUID MOTOR DUMPING SYSTEM, INCLUDING
A CYLINDER HEAD VALVE

Arthur C. Kelle, Stoughton, Mass., assignor to Allis-Chalmers Manufacturing Company, Milwaukee, Wis.

Application December 19, 1952, Serial No. 326,831

7 Claims. (Cl. 200—82)

This invention relates to circuit breakers and more particularly to pneumatically operated high speed circuit breakers.

One of the problems existing in the prior art which limited the speed of operation of a pneumatically operated circuit breaker was the excessive time needed to reclose the circuit breaker contacts. Part of the time delay in closing the contact of the circuit breaker was due to the slow acting air dumping means used to exhaust the air under pressure in the cylinder of the contact actuating fluid motor.

In order to reduce the time needed to reclose the arcing contacts, a new and improved fluid operated mechanism is provided comprising a mechanical trip free mechanism for opening and closing a pair of arcing contacts, a fluid motor having a dumping valve responsive to a difference in pressure and having a dumping area which extends along substantially the entire periphery of the head of the fluid motor for operating the trip free mechanism, and a pilot dumping valve responsive to the position of any movable element indicative of the relative completeness of the closing operation of the trip free mechanism.

It is therefore one object of the present invention to provide a new and improved pneumatic circuit breaker operating system capable of effecting high speed opening and reclosing of the circuit breaker.

Another object of this invention is to provide a new and improved pneumatic circuit breaker operating mechanism of the cylinder and piston type in which the exhaust gases are dumped in a manner which permits rapid piston reversal action.

A further object of this invention is to provide a new and improved pneumatically operated trip free operating mechanism for a circuit breaker in which the dumping action of the operating mechanism occurs in response to the position of any movable element indicative of the relative completeness of the closing operation of the trip free mechanism.

Other objects and advantages of the invention will become apparent from the following description when read in connection with the accompanying drawings, in which:

Fig. 1 is a view, partly in section, of a circuit breaker operating system in contact closed position embodying the present invention; and

Fig. 2 is a side elevation partly in section on an enlarged scale of the circuit breaker operating mechanism illustrated in Fig. 1 in contact open position.

Referring more particularly to the drawings by characters of reference, Figs. 1 and 2 illustrate a pneumatically operating trip free mechanism 11 for a circuit breaker 12. The pneumatically operating trip free mechanism 11 comprises a pneumatic motor 13 of the cylinder and piston type and a trip free type linkage 14. Motor 13 and circuit breaker 12 are operatively connected by linkage 14.

As diagrammatically shown, the circuit breaker 12 comprises a pair of stationary contact members 15 and a movable contact member 16. The circuit breaker 12 is biased to open circuit position by means of accelerating

2

spring 17. The movable contact member 16 is supported by a breaker rod 18 which, in turn, is supported by lever 19 pivoted at 20. Lever 19 is connected to the trip free operating linkage 14 by means of operating rod 21.

The operating linkage 14 comprises a lever 22 pivoted at 23 and a lever 24 pivoted at 25. Levers 22 and 24 are interconnected by a toggle comprising two toggle elements 26 and 27. Toggle element 26 is pivotally connected to lever 24 by a pin carrying a roller 28, and toggle element 27 is pivotally connected at 29 to lever 22. Toggle elements 26 and 27 are pivotally joined together by a pin 30. Pin 30 supports a roller 31 which is acted upon by an operating ram 32.

The contact closed position of the operating linkage 14 is illustrated in Fig. 1 and the contact open position of the operating linkage is illustrated in Fig. 2. In the contact closed position of the operating linkage 14, the upper position of pin 30 and roller 31 is controlled by an abutment 36. This abutment is made of any suitable resilient material and is adapted to minimize vibrations of the frame of the trip free mechanism 11 due to the impact of linkage 14 upon abutment 36. In the closed position of the circuit breaker 12, pin 30 forming the joint or connection between toggle elements 26 and 27 is supported by a spring biased prop 33 as shown in Fig. 2. Spring 34 resets linkage 14 upon a trip free operation. Spring 34 is secured at one end on the frame of the trip free operating mechanism 11 and at the other end to a lug 35 of toggle element 27.

The circuit breaker 12 is tripped by spring 17 upon a predetermined movement of a tripping mechanism 40. Tripping mechanism 40 comprises a first lever 41 pivoted at 42, a second lever 43 pivoted at 44, and a trip solenoid 45 comprising a plunger 46 adapted to act on lever 43. Plunger 46 can be operated either electromagnetically by energizing solenoid 45 or mechanically by manual means, i. e., by operation of a lever 47 pivoted at 48. Upon rotation of lever 43 about point 44 in the counterclockwise direction, lever 41 is free to pivot about pin 42 in the counterclockwise direction under the action of a force component transmitted to it by roller 28. The rotation counterclockwise of lever 41 causes counterclockwise movement of lever 24 followed by collapse of the toggle formed by toggle elements 26 and 27 and return of lever 24 to the position shown to cause the separation of the circuit breaker contacts 15, 16. Fig. 2 illustrates the linkage mechanism 14 in the toggle broken position with lever 41 reset to the latching position.

In order to close the circuit breaker 12, compressed gas is admitted to fluid motor 13 through a pipe 50, solenoid 50 valve 51, pipe 52, and a venting means or dump valve 53 comprising castings 54 and 55. Motor 13 comprises a cylinder 57 and a piston 58 which is biased downwardly by a spring 59 resting against the top of cylinder head 49 of cylinder 57. Piston 58 is provided with a stepped abutment surface 80. The cylinder head 49 is mounted in the downstream end of cylinder 57 and is provided with abutment surfaces 82 and 83 adapted to cooperate with abutment surfaces 80, 81 on piston 58. A felt cushion 84 is arranged between cylinder head 49 and a top plate 85 for receiving the shock transmitted to cylinder head 49 upon impact thereon of piston 58. Piston 58 is connected to ram 32 which coacts with roller 31 of linkage mechanism 14 to close the circuit breaker contacts 15, 16.

Casting 54 defines two passages, an intake passage 60 and an exhaust passage 61. Casting 55 defines a discharge ring providing a plurality of exhaust passages 62 separated by spacers 63. Bolts 64 passing through spacers 63 tie cylinder 57 to castings 54 and 55.

Castings 54, 55 provide the housing for dump valve 53. Dump valve 53 further comprises a plate or element 67

biased by a spring 63 in the upward direction against valve seats 69 and 70 defined by casting 55. Plate 67 is provided with perforations 71 adapted to be closed by a second nonperforated plate 72 arranged on the downstream side of plate 67, which faces piston 58. Plate 72 is biased by springs 73 against plate 67 and permits gas under pressure to flow upward only through perforation 71. The travel of plate 72 in upward direction is limited by abutments 74.

As shown in Fig. 1, dumping of gas under pressure previously admitted through passage 60 to cylinder 57 may be effected by a piston type pilot valve 88. Valve 88 comprises a cylindrical valve body 89, a valve element 90 movably arranged within valve body 89 and biased to closed position by means of a helical spring 91. Valve element 90 is in the shape of a piston with one end of spring 91 resting against the inner side of element 90 and the other end of spring 91 resting upon the base of the valve body 89. Valve body 89 is provided with an intake opening 92 and an exhaust opening 93. Pipe 94 interconnects exhaust passage 61 of the dump valve 53 with intake opening 92 of valve 88. The top of valve body 89 is provided with a screw threaded opening 98. Cylinder 57 of motor 13 is provided with an orifice 95 which is uncovered toward the end of each closing stroke of piston 58 so as to permit passage of compressed gas previously admitted to motor 13 through passage 60 to dump valve 88. A permanently open duct 96 interconnects orifice 95 with opening 98.

The circuit breaker system in Fig. 1 of the drawings is shown with the contacts 15 and 16 in the closed circuit position and the tripping mechanism in the corresponding position. Upon the energization of trip solenoid 45, plunger 46 actuates lever 43 counterclockwise about point 44. After a predetermined movement of lever 43, lever 41 is released to rotate counterclockwise about point 42 under the action of a force component transmitted to it from roller 28. The counterclockwise rotation of lever 41 releases or unlocks the tripping mechanism 14. Upon counterclockwise movement of lever 41, roller 28 moves upward under the action of spring 17 causing the collapse of the toggle formed by elements 26 and 27 and the separation of contacts 15, 16. During the collapse of elements 26, 27, pin 30 slides on prop 33.

Upon the complete collapse of the toggle formed by elements 26, 27, roller 28 settles back on its support 37, and lever 41 rotates clockwise under its biasing means to its original position where it holds roller 28 against its support 37. Trip latch 43 rotates back to its original position by the action of a spring biasing means (not shown) to hold lever 41 in its original position. The circuit breaker trip mechanism is then in the position illustrated in Fig. 2.

To close the circuit breaker contacts 15 and 16 and to return the trip free linkage 14 to the position shown in Fig. 1, solenoid valve 51 is energized to permit gas under pressure to flow from a reservoir (not shown) through pipe 50, solenoid valve 51, pipe 52, passage 60 into a chamber 97 formed by castings 54, 55 on the upstream end of plate 67. When the pressure in chamber 97 reaches a predetermined value, plate 72 is lifted from plate 67 against the bias of springs 73. The movement of plate 72 upward opens ports 71 to permit compressed air to enter cylinder 57 and to move piston 58 and ram 32 upward. The closing force of motor 13 is applied to linkage 14 by engagement of ram 32 and roller 31. Toggle elements 26 and 27 in moving upward during a closing stroke of piston 58, rotate lever 22 about its pivot point 23 in the clockwise direction. That rotary motion of lever 22 causes operating rod 21 to move downward. The downward movement of rod 21 causes lever 19 to rotate counterclockwise about its pin 20, thereby closing the breaker 12 against the action of accelerating spring 17.

When the toggle elements 26 and 27 reach prop 33 in their upward movement under the action of piston 58 and ram 32, pin 30 biases prop 33 clockwise and slides on it

until roller 31 reaches abutment 36. After pin 30 slides on prop 33, prop 33 rotates counterclockwise under the action of its biasing means 38 until it is in a position to support pin 30. Lever 41 and trip latch 43 retain roller 28 in position adjacent stop 37. The toggle formed by elements 26 and 27 is retained in contact closed position by the combined action of prop 33, lever 41 and latch 43.

A closing operation is completed when prop 33, lever 41, and latch 43 have closed the contacts and locked the toggle elements in contact closed position. Then the supply of compressed gas may automatically be shut off. This may be achieved, for instance, by a limit switch (not shown) controlled by pin 25. Assume that the circuit breaker was closed on an overload, so that upon closure of its contacts 15, 16, solenoid 45 withdraws latch 43 and does not restrain the breaker in closed circuit position. The breaker then reopens under the action of accelerating spring 17. However, the downward resetting movement of the ram is relatively slow on account of the decelerating action, or dashpot action, of fluid motor 13. Even if the supply of compressed gas is shut off from motor 13 and the lower side of motor 13 is being vented to atmosphere by prior art venting means, the decelerating effect of motor 13 might be too large to permit an instantaneous reclosing of the circuit controlled by the breaker. The dumping valve 53 shown in castings 54, 55 and dumping valve 88 are, however, so effective as to preclude any delay in the reclosure of the breaker.

Dumping of gas under pressure through inlet passage 60 to chamber 97 and cylinder 57 may be effected by piston type valve 88 and dumping valve 53. When piston 58 of motor 13 uncovers orifice 95 toward the end of its circuit breaker closing stroke, compressed gas from cylinder 57 flows through orifice 95, duct 96 into valve body 89 to depress valve element 90 against the bias of spring 91. This movement of valve element 90 effects initial opening of valve 88, permitting compressed gas from chamber 97 to enter through intake opening 92 into the body 89 of valve 88, tending to push valve element 90 farther down to uncover exhaust port or opening 93. Upon uncovering of opening 93, gas under pressure below plates 67 and 72 is free to flow through exhaust passage 61, intake opening 92, the space within valve 88 above valve element 90 and exhaust opening 93 to atmosphere. When valve 88 has been wide opened by compressed gas admitted to it through passage 61, a high pressure zone forms on top of valve element 90, tending to maintain valve element 90 in its open position against the bias of spring 91. Thus, valve element 90 remains safely in its open position when, as a consequence of the reversal of the movement of piston 58 under the action of spring 59, orifice 95 in cylinder 57 is reclosed or obstructed by piston 58 as it moves in the downward direction. In the position of valve 88 shown in Figs. 1 and 2, valve element 90 shuts off intake opening 92 from the inside of valve body 89 and, as long as this is the case, valve 88 cannot be opened by any pressure of gas in passage 61.

Upon the opening of dump valve 88, the gas under pressure in chamber 97 is exhausted to atmosphere and plates 67 and 72 are forced downward by the pressure in cylinder 57 of motor 13. The downward movement of plates 67 and 72 open exhaust passages 62 which exhaust substantially all of the gas under pressure inside of cylinder 57 and downstream of piston 58 to atmosphere. The area of passages 62 available for dumping air from the inside of cylinder 57 is equal to the entire periphery of the cylinder end extending over 360 degrees, minus the relatively small area occupied by spacers 63. The high dumping effectiveness of this circuit breaker system is predicated upon the fact that almost 360 degrees of the periphery of the cylinder head formed by castings 54, 55 have been made available for the purpose of gas dumping.

Cracking of valve 88 by compressed gas supplied through duct 96 to the top of valve element 90 occurs close to the end of each closing stroke of piston 58. There must

be sufficient power behind piston 58 to insure the movement of the latch mechanism 14 to the position at which prop 33 and latch 41 pin the toggle elements in contact closed position before compressed gas can be dumped from fluid motor 13. The moment the breaker 12 is restrained in closed circuit position, any gas under pressure within the cylinder 57 of motor 13 is instantly completely dumped. If the latch mechanism 14 performs properly upon closing of circuit breaker 12 by fluid operated motor 13, the circuit breaker remains in closed circuit position (unless it should be tripped at that time either manually or automatically). Dumping of gas under pressure through passages 61 and 62 will nevertheless occur and result in high speed reversal of the movement of piston 58 to its position in Figs. 1 and 2. Piston 58, upon having reached that position, is ready to perform another closing operation.

Initial opening of dumping valves 53 and 88 occurs irrespective of the condition of the circuit controlled by the breaker, and dumping does not depend upon the proper operation of any electroresponsive trip device. Where the operation of a valve for dumping of compressed gas from the cylinder of a fluid operated circuit breaker operating motor is made dependent upon the operation of an electroresponsive trip device, the dump valve does not afford any protection against the harmful consequences of a latch failure. Such an operating mechanism for circuit breakers would call for the provision of additional means for guarding against the harmful consequences of a latch failure, e. g., an additional dump valve which opens automatically when the supply of compressed gas is shut off from the breaker operating motor.

Mechanism 14 is trip free in that, if latch 41 is withdrawn while piston 58 is closing contact 16, lever 24 rotates counterclockwise and thereby prevents the transmission of closing effort from ram 32 to roller 31. Lever 22 therefore remains in the position shown in Fig. 2 or returns to that position if it has been moved toward or into the position shown in Fig. 1 and the circuit breaker cannot close.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In an operating mechanism for circuit breakers, a motor operable by gas under pressure and comprising a cylinder and a piston movably arranged therein, a source of gas under pressure, means for admitting gas under pressure from said source to one end of said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to cause said spring means to rapidly return said piston to said initial position thereof, said venting means comprising a valve element arranged in said end of said cylinder, resilient means for biasing said element to closed position to close said end of said cylinder, pilot means for cracking said venting means, said pilot means including a piston type valve, resilient means for biasing said piston type valve to closed position, means defining a passage from the upstream side of said element to atmosphere forming an integral part of said pilot means for reducing the fluid pressure on the upstream side of said element and for holding said pilot valve in an open position by the action of gas under pressure being vented through said passage, and means for cracking said pilot valve to open said vent-

ing means to exhaust the fluid in said cylinder to atmosphere comprising means defining an orifice in said cylinder controlled by said piston and means defining a permanently open duct for connecting said orifice to said pilot valve.

2. In an operating mechanism for circuit breakers, a motor operable by gas under pressure and comprising a cylinder and a piston movably arranged therein, a source of gas under pressure, means for admitting gas under pressure from said source to one end of said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to cause said spring means to rapidly return said piston to said initial position thereof, said venting means comprising a valve element arranged at said end of said cylinder, resilient means for biasing said element to closed position to close said end of said cylinder, means defining a one way passage through said element for fluid to flow to the downstream side of said element for providing fluid under pressure to actuate said piston, pilot means for cracking said venting means, said pilot means including a piston type valve, resilient means for biasing said piston type valve to closed position, means defining a passage from the upstream side of said element to atmosphere forming an integral part of said pilot means for reducing the fluid pressure on the upstream side of said element and for holding said pilot valve in open position by the action of gas under pressure being vented through said passage, and means for cracking said pilot valve to open said venting means to exhaust the fluid in said cylinder to atmosphere comprising means defining an orifice in said cylinder controlled by said piston and means defining a permanently open duct for connecting said orifice to said pilot valve.

3. In an operating mechanism for circuit breakers, a motor operable by gas under pressure and comprising a cylinder and a piston movably arranged therein, a source of gas under pressure, means for admitting gas under pressure from said source to one end of said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to cause said spring means to rapidly return said piston to said initial position thereof, said venting means comprising a valve element arranged at said end of said cylinder, resilient means for biasing said element to a closed position to close said end of said cylinder, means defining a passage to atmosphere controlled by said element for exhausting the said gas from said end of said cylinder, and means for reducing the pressure on one side of said element to actuate said element to valve open position, said element upon actuation to valve open position opening said passage defining means, pilot means for cracking said venting means, said pilot means including a piston type valve, resilient means for biasing said piston type valve to a closed position, means defining a second passage from the upstream side of said element to atmosphere forming an integral part of said pilot means for reducing the fluid pressure on the upstream side of said element and for holding said pilot valve in an open position by the action of gas under pressure being vented through said second passage, and means for cracking said pilot valve to open

said venting means to exhaust the fluid in said cylinder to atmosphere comprising means defining an orifice in said cylinder controlled by said piston and means defining a permanently open duct for connecting said orifice to said pilot valve.

4. In an operating mechanism for circuit breakers, a motor operable by gas under pressure and comprising a cylinder and a piston movably arranged therein, a source of gas under pressure, means for admitting gas under pressure from said source to one end of said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to cause said spring means to rapidly return said piston to said initial position thereof, said venting means comprising a valve element arranged at said end of said cylinder, resilient means for biasing said element to close said end of said cylinder, means defining a passage to atmosphere comprising an area extending over substantially the entire periphery of said cylinder, said passage defining means controlled by said element provided for exhausting to atmosphere the gas from said end of said cylinder, and means for reducing the pressure on one side of said element to actuate said element to valve open position to exhaust gas under pressure from the upstream side of said piston through said passage to atmosphere, pilot means for cracking said venting means, said pilot means including a piston type valve, resilient means for biasing said piston type valve to closed position, means defining a second passage from the upstream side of said element to atmosphere forming an integral part of said element for reducing the fluid pressure on the upstream side of said element and for holding said pilot valve in an open position by the action of gas under pressure being vented through said second passage, and means for cracking said pilot valve to open said venting means to exhaust the fluid in said cylinder to atmosphere comprising means defining an orifice in said cylinder controlled by said piston and means defining a permanently open duct for connecting said orifice to said pilot valve.

5. In an operating mechanism for circuit breakers, a motor operable by gas under pressure and comprising a cylinder and a piston movably arranged therein, a source of gas under pressure, means for admitting gas under pressure from said source to said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to cause said spring means to rapidly return said piston to said initial position thereof, said venting means comprising a differential valve element arranged at said end of said cylinder, resilient means for biasing said element to close said end of said cylinder, means defining a discharge ring surrounding said element for providing a plurality of passages to atmosphere, means for reducing the pressure on one side of said element to actuate said element to open position to exhaust gas under pressure from said end of said piston through said passages to atmosphere, and pilot means for cracking said venting means, said pilot means including a piston type valve, resilient means for biasing said piston type valve to closed position, means defining a passage from the upstream side of said element to atmosphere forming an integral part of said element for reducing the fluid pressure on the upstream side of said element for reducing the fluid pressure on the

upstream side of said element and for holding said pilot valve in open position by the action of gas under pressure being vented through said passage, means for cracking said pilot valve to open said venting means to exhaust the fluid in said cylinder to atmosphere comprising means defining an orifice in said cylinder controlled by said piston and means defining a permanently open duct for connecting said orifice to said pilot valve.

6. In an operating mechanism for circuit breakers, a motor operable by gas under pressure and comprising a cylinder and a piston movably arranged therein, a source of gas under pressure, means for admitting gas under pressure from said source to one end of said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to atmosphere to cause said spring means to rapidly return said piston to said initial position, said venting means comprising a valve element arranged at said end of said cylinder, resilient means for biasing said element to close said end of said cylinder, means defining a passage to atmosphere comprising an area extending over the entire periphery of said cylinder, said passage defining means controlled by said element, and means for reducing the pressure on the upstream side of said element to actuate said element to valve open position to exhaust gas under pressure from said cylinder through said passage to atmosphere, said pressure reducing means comprising a piston type valve, resilient means for biasing said piston type valve to closed position, means defining a passage from the upstream side of said element to atmosphere forming an integral part of said pressure reducing means for reducing the fluid pressure on the upstream side of said element, and means for cracking said pressure reducing means to open said venting means to exhaust the fluid in said cylinder to atmosphere.

7. In an operating mechanism for circuit breakers, a motor operable by gas under pressure and comprising a cylinder and a piston movably arranged therein, a source of gas under pressure, means for admitting gas under pressure from said source to one end of said cylinder to close the breaker, spring means for returning said piston to the initial position thereof upon closing of the breaker, a collapsible linkage of the trip free type for operatively relating the breaker to said motor, tripping means for causing collapse of said linkage to cause opening of the breaker, a ram on said piston separate from said linkage and cooperating therewith upon collapse thereof for reclosing the breaker, means for venting said cylinder to atmosphere to cause said spring means to rapidly return said piston to said initial position, said venting means comprising a valve element arranged at said end of said cylinder, resilient means for biasing said element to close said end of said cylinder, means defining a discharge ring surrounding said element for providing a plurality of passages to atmosphere, means for reducing the pressure on the upstream side of said element to actuate said element to valve open position to exhaust gas under pressure from said cylinder through said passages to atmosphere, said pressure reducing means comprising a piston type valve, resilient means for biasing said piston type valve to closed position, means defining a passage from the upstream side of said element to atmosphere forming an integral part of said pressure reducing means for reducing the fluid pressure on the upstream side of said element and for holding said pilot valve in an open position by the action of gas under pressure being vented through said passage, and means

for cracking said pilot valve to open said venting means to exhaust the fluid in said cylinder to atmosphere comprising means defining an orifice in said cylinder controlled by said piston and means defining a permanently open duct for connecting said orifice to said pilot valve. 5
